UNITED STATES PATENT OFFICE.

JOHN R. WARREN, OF GRAND RAPIDS, MICHIGAN.

LIFTING-TONGS.

1,249,568.

Specification of Letters Patent. Patented Dec. 11, 1917.

Application filed January 11, 1915. Serial No. 1,536.

To all whom it may concern:

Be it known that I, JOHN R. WARREN, a citizen of the United States, residing at Grand Rapids, in the county of Kent and State of Michigan, have invented new and useful Improvements in Lifting-Tongs, of which the following is a specification.

My present invention relates to lifting tongs, and its object is to provide a device of that character which shall be simple and economical in construction and easy and efficient in operation.

This and any other objects appearing hereinafter, are attained by, and the invention finds preferably embodiment in the structure hereinafter described and illustrated by the accompanying drawings, in which:—

Figure 1 is a view in perspective of such structure:

Fig. 2 is a fragmentary view of the same applied to lift a vessel, as a pan:

Fig. 3 is a like view illustrating a different application:

Fig. 4 is a longitudinal section of said structure; and

Fig. 5 is a fragmentary bottom plan view of the same.

The body portion 1 of one of the arms 2 of any lifting tongs is preferably of sheet-metal bent to form a suitable handle 3 at one end and folded at 4 to closely embrace the ends of the wire object-engaging portion 5 which is provided with three object-engaging points, two —6— being located on its sides and the other 7 at its extremity, such points being formed by bending the wire. These object-engaging points are triangularly-disposed as shown, so as to firmly engage one side of the object to be lifted, as the vessel or pan 8, although such object may have a curved surface of various forms.

The other arm 9 is hinged to the arm 2, preferably by a pivot pin 10, seated in a recess 11 in the arm 2 and securely held therein by the wire portion 5 when the body portion 1 is folded to embrace such wire portion, as particularly shown in Figs. 4 and 5.

This arm 9 has an object engaging point 12 adapted to engage the opposite side of the object, as the pan 8, coöperating with the engaging points of the arm 2 within the triangular limits of their disposition. Such engaging points 12 may, by the relative movement of the arms, be brought to object-engaging positions on both sides of the plane

in which the engaging points 6 and 7 lie, whereby arcuate surfaces as the side of a pan, as shown, may be securely held in my tongs. The wire portion 5 surrounds the arm 9 affording engaging points on each side thereof and outside its free end 13, as shown.

A second engaging point 14 may be provided near the free end of the arm 9, hook-shaped as shown, and adapted to engage and hold as, a hook, an object, as the pan shown in Fig. 2.

A coöperating handle portion 15 pivoted to the arm 2 and spring-pressed at 16 to open the arms may be adapted to operate the tongs, as through a rod 17 connected to the arm 9.

It will be seen furthermore, that the arm 2 has concave object-engaging surfaces on both sides extending between the points 6 and 7, and that the arm 9 has a similar concave object-engaging surface extending between the points 12 and 14, the arms being relatively movable to positions on both sides of a straight line connecting the lowest points of said surfaces, whereby any such object as a table knife or fork, etc., may be readily picked up.

Not confining myself to details of construction shown or described, I claim:—

1. Lifting tongs having one arm with three triangularly disposed object-engaging points, and a second arm with an object-engaging point coöperating with said other points within the triangular limits of their disposition, the three object-engaging points of the first arm being separated by object-nonengaging portions of the first arm.

2. Lifting tongs having two arms, one of which is provided with object-engaging points on both sides of and outside the free end of the other arm, said other arm being provided with an object-engaging point movable to operative positions on both sides of the plane of the first mentioned arm's engaging points.

3. Lifting tongs having one arm, comprising a sheet-metal body portion and an engaging-point carrying portion of bent wire attached to the body portion by folding the body portion to closely embrace said wire, and a second arm hinged to the first-mentioned arm by a pivot pin, the sheet-metal body portion having a recess to hold the pivot pin and the wire portion confining the pivot pin in such recess.

4. Lifting tongs having one arm with three triangularly disposed object-engaging points, and a second arm having an object-engaging point coöperating with said other points within the triangular limits of their disposition and having also an object-engaging hook, the three object-engaging points of the first arm being separated by object-nonengaging portions of the first arm.
5. Lifting tongs having two arms, one of which is provided with concave object-engaging surfaces on both sides of the free end

of the other arm, said other arm being provided with a concave object-engaging surface movable to operative positions on both sides of the direct line between the lowest points of said surfaces. 15

In testimony whereof I have hereunto set my hand in presence of two subscribing witnesses.

JOHN R. WARREN.
